US0D1077859S

(12) **United States Design Patent** (10) **Patent No.:** **US D1,077,859 S**
(45) **Date of Patent:** **** Jun. 3, 2025**

(54) **BLOWER**

(71) Applicant: **MILWAUKEE ELECTRIC TOOL CORPORATION**, Brookfield, WI (US)

(72) Inventors: **Bennett W. Westling**, Milwaukee, WI (US); **Atul Anand**, Milwaukee, WI (US)

(73) Assignee: **Milwaukee Electric Tool Corporation**, Brookfield, WI (US)

(**) Term: **15 Years**

(21) Appl. No.: **29/758,626**

(22) Filed: **Nov. 17, 2020**

(51) LOC (15) Cl. **15-02**

(52) U.S. Cl.

USPC **D15/12**

(58) **Field of Classification Search**

USPC D15/5, 12; D32/15

(57) **CLAIM**

The ornamental design for a blower, as shown and described.

DESCRIPTION

FIG. 1 is a perspective view of a blower.

FIG. 2 is a right elevation view of the blower shown in FIG. 1.

FIG. 3 is a left elevation view of the blower shown in FIG. 1.

FIG. 4 is a front elevation view of the blower shown in FIG. 1.

FIG. 5 is a rear elevation view of the blower shown in FIG. 1.

FIG. 6 is a top plan view of the blower shown in FIG. 1; and, FIG. 7 is a bottom plan view of the blower shown in FIG. 1.

The broken lines represent portions of the blower that form no part of the claimed design.

1 Claim, 7 Drawing Sheets
